UNITED STATES PATENT OFFICE.

JESSE M. SIZEMORE, LEM B. JONES, AND EDMOND D. SIZEMORE, OF AUGUSTA, GEORGIA.

BUNCH BUILDER.

Application filed May 5, 1927. Serial No. 188,994.

This invention relates to bunch builders for spinning machines, wherein the yarn is first wound upon the bobbin to form a primary winding or bunch and thereafter a secondary or main winding of the yarn is laid upon the bobbin to complete the building of the yarns thereon.

In the winding of thread and yarn on filling bobbins it is customary to form a primary winding or bunch which is adapted to come into contact with a feeler carried on the loom which serves as an indicating means when the yarn has been unwound to a predetermined extent, and the operator is then enabled at the proper time to remove the unwound bobbin and replace a full bobbin therefor. It is obvious that should the bunch not be placed in a proper position on the bobbin, the same will be ineffective to properly operate the feeler, thus resulting in imperfect weaving, and the production of defective goods. It is accordingly the purpose of our invention to produce a perfect bunch in the same position on all bobbins and with this object in view, we provide a positive gear drive and provide means for effectively retaining the device out of bunching position until after the ring rail has been moved into its lowermost position by the operator as customary when beginning the winding of a fresh bobbin, thereby preventing any imperfection in the main winding by the bunch builder.

Other objects and advantages reside in the specific construction, combination and arrangement of the various elements forming the invention as more fully hereinafter described and claimed, reference being had to the accompanying drawing, forming a part hereof, wherein like numerals refer to like parts throughout and in which:

Figure 1 is a front elevation of a portion of a spinning frame, with our invention shown in operative position thereof.

Figure 2 is an enlarged side elevational view, showing the bunch building mechanism.

Figure 3 is a top plan view thereof.

Figure 4 is a detail showing the bunch builder in inoperative position, and

Figure 5 is a similar view showing the same in position ready to begin operation.

Referring now to the drawing, we have shown our invention as adapted for use upon a spinning frame indicated at 5, upon which

is arranged the usual spindle reel 6, provided with rotatable spindles for the bobbin 7, adapted to be carried on the vertically reciprocating spinning wheel 8.

A lift rod 9 extends downwardly from the ring rail and is adapted to be actuated at its lower end by a pivotally mounted rocker arm 10, having a weight 11 at one end thereof. An arm 12 is attached to the arm 10, the arm 12 having a cable 13 attached thereto extending over a pulley 14 and to which a chain 15 is attached engaging a socket 16, keyed on a stub shaft 17. The shaft 17 extends laterally from an oscillating bunch building arm 18, pivotally mounted by a pin 19, secured to the main frame.

A cam 20 is mounted upon a shaft 21, rotatably supported by the main frame, said shaft being operated by any suitable means, the cam being adapted to engage a ruler 22 arranged on the arm 18. The cam 20 contacting with the ruler 22 operates to oscillate the arm 18 whereby to raise and lower the ring rail during the main winding of the bobbin.

To the arm 18 is fixedly secured a substantially U-shaped bracket 23 by a bolt 24. Between the arms of the bracket is pivotally mounted the lower ends of a separating arm 24, upon a shaft 25. The arm 24 is arranged in section including an upper section 25 and a lower section 26 as shown in Figure 2 of the drawing and provided with slots 27 at their connected ends thereby to secure the same in extended position by bolts 28. The upper end of the section 25 is provided with a gear segment 29 which is provided with alternating sections of short teeth 30 and relatively long teeth 31. The gear segment 29 is arranged to engage a gear wheel 32, concentrically arranged with the cam 20 on the cam shaft 21. An angularly constructed trip arm 33 is provided, having one end rotatably supported between the arms of the U-shaped bracket 23 and the opposite end extending upwardly and over a roller 34, extending from the main frame, a weight 35 being secured on the free end of the trip arm. The portion of the arm engaged by the roller is of a substantially U-shaped formation, invertedly arranged and adapted to rock back and forth on the roller as the building arm 18 is oscillated. Figures 4 and 5 of the drawing show the extent of movement of the arm upon the roller, Figure 4 showing the

relation of the arm with the gear segment in extreme rearward position, whereas Figure 5 shows the bar in an opposite position.

Mounted on the opposite end of the arm 33 is keyed a trip 36, the trip being arranged to engage one edge of the arm 24 carrying the gear segment. To the outer edge of the bracket 23 is secured a U-shaped arm rest 37, the sides of the arm rest defining the limitation of the forward and backward movement of the gear segment arm 24.

It will be noted that the said trip 36 is arranged to engage the rear edge of the cam segment arm 24 so that when the building 15 arm 18 is moved into its lowermost position to begin the winding of the yarn, the trip will operate to move the gear segment forwardly as shown in Figure 5. Thus, the first motion imparted to the cam shaft 21 will cause 20 the gear segment to move forwardly to the position shown by Figure 4, this movement being completed before the main winding action of the cam 20 has started. Because of the variation in the size of the gear segment, 25 the building arm will be caused to quickly oscillate sufficiently to produce the primary or bunch winding. As soon as the bunch has been filled, the cam then produces its first full stroke, and the gear segment re- 30 mains idle in its forward position until the main winding has been completed and the bobbin changed.

It is to be understood that various changes or modifications in the details of construction and arrangement may be made without departing from the spirit of the invention or the scope of the appended claims.

We claim:

1. An apparatus of the character described 40 comprising a builder arm having an actuating cam, and a bunch builder secured to the arm including a gear segment pivotally attached thereto, alternately arranged strips of short and long teeth formed on said segment, a trip actuated by the arm to move the segment forwardly, and a bunch builder gear operatively engageable with the teeth of the segment to move the same rearwardly.

2. An apparatus of the character described 50 comprising a builder arm having an actuating cam, a bunch builder secured to the arm including an extensible gear segment pivotally attached thereto, alternately arranged sets of different sized teeth formed on said segment, a trip actuating by the downward movement of the arm to move the segment forwardly, and a bunch builder gear operatively engageable with the teeth of the segment to move the same rearwardly.

60 3. An apparatus of the character described

comprising a builder arm having an actuating cam, a bunch builder secured to the arm including an extensible gear segment pivotally attached thereto, alternately arranged sets of different sized teeth formed on said segment, and an angular arm pivotally attached at one end to the builder arm, means 65 engaging the angular arm tending to cause the same to rock forwardly and backwardly, a trip actuated by said angular arm and engaging said segment whereby to move the same forwardly, and a bunch builder gear operatively engageable with the teeth of the segment to move the same rearwardly. 70

4. An apparatus of the character described 75 comprising a builder arm having an actuator cam, a bunch builder secured to the arm including a bracket fixedly attached thereto, an extensible gear segment pivotally carried by the bracket, and having alternately arranged sets of different sized teeth formed thereon, an angular arm pivotally carried by the bracket, means engaging said angular arm tending to cause the same to rock forwardly and backwardly, a trip secured to said angular arm and engageable with said segment whereby to move the same forwardly, a bunch builder gear operatively engageable with the teeth of the segment to move the same 80 rearwardly and stop means secured to the bracket limiting the forward and rearward movement of said segment. 85

5. An apparatus of the character described 90 comprising a builder arm having an actuator cam, a bunch builder secured to the arm including a gear segment, teeth of irregular formation provided on said segment, a bunch builder gear concentrically arranged with respect to said cam and operatively engageable with the teeth of said segment and means for radially adjusting said segment with respect to said gear. 95

6. An apparatus of the character described 100 comprising a builder arm having an actuating cam, a bunch builder secured to the arm including a gear segment pivotally attached thereto, alternately arranged series of short and long teeth formed on said segment, a trip actuated by the arm to move the segment in one direction, means engageable by the gear whereby to oppositely move the same and means carried by the trip normally restraining movement of the segment in said first named direction. 105

In testimony whereof we affix our signatures. 115
